UNITED STATES PATENT OFFICE.

WALLACE C. BROWN, OF NANTUCKET, MASSACHUSETTS.

DESIGN FOR A CLOCK-CASE.

SPECIFICATION forming part of Design No. 23,026, dated January 30, 1894.

Application filed December 20, 1893. Serial No. 494,204. Term of patent 14 years.

To all whom it may concern:

Be it known that I, WALLACE C. BROWN, of Nantucket, in the county of Nantucket and State of Massachusetts, have invented a new and original Design for a Clock-Case, of which the following is a full, clear, and exact description.

Reference is to be had to the accompanying drawing forming a part of this specification, in which is represented a face view of a clock case embodying my new design.

The leading feature of my design consists of the base A, body B, and top C, the body being narrower than the base and top and having spiral columns D at the front, at the corners, in recesses d, and the top C having spiral columns E at the corners outside the lines of the body B, their lower ends resting on a ledge c, and their upper ends joining the lateral extensions c' of an arched molding c² on the top C.

Minor features of the design consist of the molding a at the juncture of the base and body, the molding b at the juncture of the body and top, the figures d at each end of the top C, above the molding c², said figures d having a cylindrical base and a conical top, the conical figure e at the center of the molding c², above the same, and the ornamentation above the dial D, said ornamentation comprising a segmental field on which appears the partial representations of the hemispheres f, the stars g, and the circular figure h having thereon the representation of the human eyes, mouth and nose. 35

I claim—

The design for a clock case herein shown and described.

WALLACE C. BROWN.
